UNITED STATES PATENT OFFICE.

JAMES H. WALKER, OF MILWAUKEE, WISCONSIN, ASSIGNOR TO THE FULLER-WARREN CO., OF MILWAUKEE, WISCONSIN, A CORPORATION OF WISCONSIN.

GAS-STOVE.

1,199,842.

Specification of Letters Patent.

Patented Oct. 3, 1916.

Original application filed May 8, 1912, Serial No. 695,818. Divided and this application filed July 22, 1914. Serial No. 852,518.

To all whom it may concern:

Be it known that I, JAMES H. WALKER, a citizen of the United States, residing at Milwaukee, in the county of Milwaukee and 5 State of Wisconsin, have invented certain new and useful Improvements in Gas-Stoves, of which the following is a specification, reference being had to the accompanying drawing, forming a part thereof.

10 The main objects of this invention are to construct and arrange the burners of a gas range or stove and their connections so that they will be easily accessible and unaffected by the heat of the stove and so that the 15 burners may be readily and separately removed for cleaning and repairing the same; to locate the cocks or valves controlling the supply of gas to the burners where they will be out of the way and not liable to be accidentally displaced, but can be readily operated by suitable connections; and generally 20 to improve the construction, arrangement and operation of the burners and their connections for gas ranges or stoves.

25 The invention consists in the construction, arrangement and combination of parts as hereinafter particularly described and pointed out in the claims.

In the accompanying drawing like characters designate the same parts in the several figures.

Figure 1 is an end elevation of a gas stove or range embodying the invention; Fig. 2 is a plan view of one end of the stove or 35 range with the top plate removed; and Fig. 3 is a vertical section on the line 3—3, Figs. 1 and 2.

The stove or range comprises a top frame *a*, a top plate *b*, end walls *c*, one of which is 40 shown, and side walls *d*. A horizontal wall *e*, located below the frame *a*, forms with the top plate *b* and end and side walls *c* and *d*, a heating compartment or combustion chamber *f*, which is preferably divided into longitudinal flues or channels by partitions *g*. The heating compartment or combustion chamber *f*, is provided at the bottom with a lining *h* of fire brick or other refractory heat absorbing and reflecting material, as 45 shown in Fig. 3.

The stove or range is provided at the end with a number of separately removable burners comprising vertical flues or mixing tubes *i*, having air inlet openings at their

lower flaring or enlarged ends *j*, and laterally bent upper end or heads *k*, which open into the heating compartment or combustion chamber *f* in the direction of the length of the flues into which it is divided, and preferably close to the top plate *b*.

55 The burners and their gas supply connections are located outside of the stove or range, where they are unaffected by the heat and are accessible as well as out of the way.

60 The laterally bent heads *k* at their upper ends are inserted in openings formed therefore in the end wall *c*, and are formed or provided with studs or lugs *l*, which by engagement with said end wall hold the burners in place.

65 A gas supply pipe or manifold *m*, is supported in a horizontal position across the end of the stove or range by brackets *n*, attached to the end wall *c*.

70 At their lower ends the burners are formed or provided with centrally perforated spiders or cross pieces which are loosely and removably fitted on the nipples *o* of the cocks or valves *p* connected with the gas supply pipe or manifold *m*, and forming gas 75 passages between said pipe or manifold and the lower ends of the flues or mixing tubes *i* of the burners.

75 Disks *q*, for adjusting and regulating the supply of air admitted into the lower ends 80 of the flues or mixing tubes *i* of the burners, are threaded on the nipples *o*, as shown in Fig. 3. The burners are loosely supported at their lower ends on the nipples *o* of the gas cocks or valves *p*, and at their upper 85 ends by the heads *k* in the end wall *c* of the stove or range. They are removably secured in place by a metal band or bracket *r*, fastened to the end wall *c* of the stove or range, and by clamping bars or bands *s*, which are 90 connected with the band or bracket *r* by screws or other suitable means. By detaching the clamping bars or bands *s* from the bracket or band *r*, or by turning them into an upright position, any of the burners may 95 be readily removed from the stove or range independently of and without disturbing the others.

100 To facilitate the operation of the gas cocks or valves *p*, which are located at the end of the stove or range where they are out of 105 the way and not liable to be accidentally turned or displaced, rods *t*, are pivotally

connected at one end with crank arms *u* on the stems of the cocks or valves, and extend therefrom upwardly and obliquely to the front of the stove or range, where they are guided in a vertical plate or bar *v*, attached to the stove or range. At their front ends the rods *t* are provided with knobs or handles *w*, which are preferably arranged in a vertical series within clear view and convenient reach of the operator, thereby not only facilitating the operation of the cocks or valves, but also indicating at a glance which of them are open and which are closed.

To admit an additional supply of air to the heating compartment or combustion chamber *f*, or to the flues into which it is divided by the partitions *g*, for producing and maintaining complete combustion of the fuel gas, openings *x* are formed in the end wall *c* of the stove or range below the discharge openings at the upper ends of the burners.

In the operation of the stove or range the cocks or valves *p*, of any desired number of burners according to the amount and kind of work to be done, being opened by pulling the knobs or handles *w* controlling such burners forward, the combustible mixture of gas and air issuing from the discharge openings at the upper ends of the burners is lighted and produces broad jets or sheets of flame which are directed lengthwise of the flues along and in contact with the top plate *b*, more or less of which is heated sufficiently for performing the desired cooking operations thereon.

When the burners have been in operation for some time, the fire brick or other refractory bottom lining *h* of the combustion chamber becomes incandescent or highly heated, reflecting heat to the top plate and aiding combustion of the fuel gas.

After the refractory lining and walls of the combustion chamber or flues have become highly heated, the gas supply to alternate burners or to some of the burners may be shut off, and the required degree of heat for such cooking operations as are in progress may be maintained by the operation of the remaining burners. When a small or limited amount of cooking is to be done, only that portion of the top plate which is required, needs to be heated, the burners supplying other portions remaining out of use, thus economizing in the consumption of fuel.

The location of the burners entirely outside of the stove or range, where they are not subjected to great variations of temperature, avoids variations in the supply of air thereto and in the resulting mixture of air and fuel gas, thereby maintaining the proper quality of the burner flames for the production of the greatest amount of heat for a

given consumption of gas, whatever length of time the burners may be in use. This location of the burners also prevents carbonization and reduced efficiency thereof resulting in variation in the temperature and 70 overheating of the mixture before ignition takes place, and avoids the necessity of constant attention and frequent adjustment and regulation of the gas and air supply to the several burners.

The construction and arrangement of the burners shown and described also admit of readily removing any of the burners for cleaning, repairing or renewing the same independently of the others, and afford easy 80 access thereto as well as to their gas supply connections and controlling cocks or valves and the adjustable disks *q*, for regulating the supply of air to the lower ends of the vertical flues or mixing tubes of the burners. 85

Various modifications in minor details of construction and arrangement of parts may be made without departing from the principle and scope of the invention as defined in the following claims.

This application is a division of my application Serial No. 695,818, filed May 8, 1912, for improvements in gas ranges.

I claim:

1. The combination of a stove and a gas heating appliance comprising, a gas manifold, a plate at one side of the heating compartment of the stove, said plate formed with openings therein, gas burners, each burner having a flue and discharge head, the discharge head extending through one of said openings in said plate, the burner being supported by said plate, and a gas passage for each burner communicating with the manifold and discharging in said flue.

2. The combination of a stove and a gas heating appliance comprising, a gas manifold, a side member of the heating compartment of the stove formed with openings 110 therein, gas burners, each burner having a flue and discharge head, the discharge head extending through one of said openings, the burner resting on said side member and having a stud for contacting the side member 115 and holding the burner in position, and a gas passage for each burner communicating with the manifold and discharging in said flue.

3. The combination of a stove and a gas heating appliance comprising, a gas-manifold, a side member of the heating compartment of the stove formed with openings 120 therein, gas burners, each burner having a flue, a discharge head and an air intake portion at the end of the flue opposite said discharge head end, the discharge head extending through one of said openings, a gas 125 passage for each burner communicating with the manifold and discharging into said 130

flue at the air intake portion thereof, and a loose connection between the burners and said side member, adjacent the discharge head and from which the burners are detachable.

4. The combination of a stove and a gas heating appliance comprising, a gas supply pipe, a side member of the heating compartment of the stove having an opening therein, a gas burner having a flue and discharge head, the discharge head extending through said opening, the burner adapted to rest on said side member and having a stud for contacting the side member and holding the burner in position, a gas passage communicating with the gas supply pipe and discharging in said flue, and a valve for controlling the supply of gas to the burner.

5. The combination of a stove and a gas heating appliance comprising, a gas supply pipe, a side member of the heating compartment of the stove having an opening therein, a gas burner having a flue, a discharge head and an air intake portion at the end of the flue opposite the discharge head, said head extending through the opening in

the said member, a gas passage communicating with the gas supply pipe and discharging into the flue at the air intake portion thereof, a valve controlling the supply of gas to said burner, and the burner being supported by the side member and detachable therefrom.

6. In a gas stove the combination of a combustion chamber having a side wall formed with burner openings, a horizontally disposed gas supply pipe located outside of said wall below said chamber and having branches provided with valves, and burners consisting of vertically disposed mixing tubes having air inlet openings at their lower ends which are removably connected with the branches of the gas supply pipe, and laterally bent discharge heads at their upper ends which are removably fitted and held in the openings of said side wall.

In witness whereof I hereto affix my signature in presence of two witnesses.

JAMES H. WALKER.
